[57] CLAIM

The ornamental design for a pacifier, as shown and
described.

DESCRIPTION

FIG. 1 is a perspective view of a pacifier, showing our new
design;

FIG. 2 is a second perspective view of the pacifier of FIG.
1;

FIG. 3 is a front view of the pacifier of FIG. 1;

FIG. 4 is a rear view of the pacifier of FIG. 1;

FIG. 5 is a side view of the pacifier of FIG. 1, wherein an
opposite side view would be a mirror image thereof;

FIG. 6 is a top view of the pacifier of FIG. 1; and,

FIG. 7 is a bottom view of the pacifier of FIG. 1.
